Gautreau, Somersville, Conn.

Application July 28, 1941, Serial No. 404,276

2 Claims. (Cl. 139—273)

Our invention relates to improvements in weaving apparatus and it is directed more particularly to improvements in feeler devices for use on looms and the like. This application is a continuation in part of an application Ser. No. 345,760, filed by us July 16, 1940.

The principal objects of the invention are directed to the provision of a feeler device for a loom which is adapted to contact the yarn on a bobbin or a bobbin when empty and to operate when the bobbin is empty to close an electric circuit controlling the operation of mechanism which replaces an empty bobbin in the shuttle with a filled one.

The feeler device of the invention is positioned on the loom so as to be engaged or acted upon by the bobbin when the shuttle carrying the bobbin is in the shuttle box of the lay and said lay is moved back and forth for the beating operation. When the lay moves back and forth for a beating operation, an empty bobbin engages and acts on the feeler device to cause it to close an electric circuit in which is included the operating mechanism for replacing an empty bobbin in the shuttle with a filled one. With a filled or partially filled bobbin or in fact until the yarn on the bobbin is substantially exhausted, the feeler device although contacted by the yarn in the bobbin is not actuated to operate the bobbin replacing mechanism.

The feeler device of the invention is characterized by its simplicity of construction and its efficiency and sensitiveness in operation. It functions as a circuit closing device and controls the operation of the bobbin feeding mechanism in such a way that empty bobbins in the shuttle or shuttles are replaced with filled ones without in any way interfering with the operation of the loom although the lay swings back and forth at high speed.

The device of the invention is characterized by a slide which is reciprocable in a bracket that is engaged by the yarn on a filled bobbin in such a way as to be moved inwardly against the action of spring means and it has a spring pressed pilot reciprocable in the slide having an outer pointed end adapted to impinge the yarn on a bobbin or to be engaged by an empty bobbin and moved thereby relative to the slide for closing an electric circuit.

The pilot moves in a straight line back and forth relative to the slide and its forward pointed end may protrude various distances beyond the forward end of the slide to accommodate yarn of various sizes and characteristics.

The said forward end of the pilot is disposed centrally relative to the forward yarn engaging end of the slide thereby to insure that the end of the slide engages the yarn at a point over a point on the bobbin which would be engaged by the pilot except for the yarn. This obviates the possibility of the pilot being moved to switch closing position when in fact the bobbin is not empty.

The pilot has an outer relatively sharp or conically pointed end so as to be adapted to impinge the layers of yarn on a bobbin or pass between convolutions thereof. If not so pointed it is likely to be moved relative to the slide which would move it to switch closing position and a pointed end provides a relatively sharp point so that its contact with the empty bobbin is small thereby to insure accuracy in operation and not cut or injure yarn on a bobbin as would be the case were the end of the pilot of considerable dimension.

Various novel features and advantages of the invention will be hereinafter more fully referred to in connection with the accompanying description of the present preferred form thereof taken in connection with the drawing, wherein:

Fig. 1 is a plan view of the feeler device of the invention;

Fig. 2 is an inverted plan view of the same; and

Fig. 3 is a side elevational view of the device shown in Figs. 1 and 2.

Referring now to the drawing more in detail, wherein similar reference figures refer to like parts, and referring more particularly to the preferred form of our invention which has been selected for illustrative purposes, the invention will be described.

A bracket or support is shown at 2 which is grooved at 4 for a slide 6 that is reciprocable back and forth therein.

40 The slide 6 is preferably in the form of a T having a transverse member 8 at its rear or inner end. An end part 10 of the support is slotted at 12 and a spring anchor 14 on the bottom of the slide extends through said slot.

45 A second spring anchor 16 is secured to the bottom of the bracket 2 and a tension spring 18 has its opposite ends secured to the said anchors. The spring urges the slide outwardly or to the right relative to the bracket. The slide is limited 50 in its movement outwardly or to the right by the transverse member 8 abutting the left hand or inner end of the bracket.

A cap 20 is provided on the bracket over the slide groove and is secured in place to overlie 55 the slide by screws 22. A part 24 on the cap is

slotted at 26 to facilitate securing of the device to a loom. Any other desired form of part 24 and cap may be employed in order to secure the device to looms of various types.

The slide 6 is hollow or is bored at 30 and a pilot 32 extends entirely therethrough and is slidable therein. A spring 34 around the pilot in a recess 36 of the slide is disposed between an end of the recesses and a pin 37 on the pilot to urge the said pilot outwardly or to the right relative to the slide. A pair of nuts 38 on the inner threaded end of the pilot limit outward movements of the pilot relative to the slide. These nuts are arranged so that as the pilot is moved outwardly by spring 34 its forward pointed end 40 may be made to project different distances beyond the end 7 of the slide 6 thereby to accommodate yarns of different types.

The outer end of the pilot is conical or pointed, the material of which the pilot is made being cylindrical so that the end is relatively sharp. This is desirable for the reason it is desired that the end of the pilot impinge yarn on the bobbin or pass between the yarn windings. Were the pilot end of considerable area as distinguished from a point the pilot is likely to be moved relative to the slide by the yarn.

An insulator 44 and a yieldable contact 46 thereon are secured to the transverse part 8 of the slide 6 by any suitable means such as a screw 48 and a screw and nuts 50 and 52 of the contact is for receiving a wire of a circuit. A screw 54 on the member 8 is for another wire of a circuit.

The device may be secured to a loom by means of the securing part 24 in such a position that the forward or outer end of the slide 6 is positioned so that the swinging lay moves a bobbin in a shuttle towards and away from the end of the slide 6. The parts 46 and 54 are connected in a circuit including the bobbin changing operating mechanism which as well known operates when the circuit is closed to replace an empty bobbin with a filled one.

As the lay moves toward the feeler device associated with a loom in the manner referred to the end of the slide passes through a slot in the bobbin shuttle. The end 7 of the slide is engaged by the yarn on the bobbin in the shuttle so that the slide is depressed or moved inwardly or to the left carrying with it the pilot. The sharp outer or forward end of the pilot impinges the yarn on the bobbin.

This movement of the slide is against the action of spring 18 so that the slide moves outwardly when the lay moves away from the device again.

Because the pilot has a sharp pointed end it impinges the yarn on the bobbin or passes between the windings thereof and moves with the slide rather than relative thereto as would be the case were the end of the pilot of considerable area so that it was acted upon by the yarn.

Should the bobbin be empty the bobbin engages the sharp point 40 of the pilot to move the pilot inwardly or rearwardly relative to the slide causing the inner end of the said pilot to engage contact 46 and close the circuit.

The pilot and in fact the feeler device being in one side of a circuit and the contact in the other, the engagement of the pilot directly with the contact provides a switch action to close the circuit thereby causing the bobbin changing mechanism to operate to replace the empty bobbin with a filled one.

In each alternate movement of the lay in one direction it carries the shuttle holding the bobbin towards the device so that the slide is moved inwardly by yarn on the bobbin or the pilot is moved inwardly relative to the slide by a bobbin when empty.

The movement of the pilot relative to the bobbin depends on the distance the pilot end protrudes beyond the slide and the distance may be made to accommodate yarn of different types or sizes.

The pilot is movable back and forth in a straight line and the inner end thereof directly engages the contact and co-operates therewith for the switch action. This is very important for the reason the switch is closed instantaneously so that the empty bobbin is thrown out and replaced by a filled one all within a very short space of time, that is as the lay arrives at the end of its stroke and quickly moves away therefrom in an opposite direction.

The pointed end of the pilot 40 is centrally disposed relative to the end 7 of the slide. It is important that the end of the slide engaging the yarn on a bobbin overlie the point on the bobbin that would be engaged by the pilot except for the yarn. Otherwise due to improper winding of the yarn on the bobbin and other causes the end of the slide may engage yarn on a bobbin while at the same time the pilot may engage a bare part of the bobbin at a point spaced therefrom causing a partly exhausted bobbin to be replaced, thereby wasting yarn.

The area of the yarn engaging end of the slide is of relatively small area so that with the pilot end disposed centrally thereof there is no danger of the slide end engaging yarn while the pilot engages a bare bobbin at some distance therefrom. Either the slide end is engaged by yarn or the pilot end is engaged by the bare bobbin.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. A feeler device comprising in combination, a support having a slide guideway, a slide reciprocable in the guideway having an outer end provided with an end surface adapted to be engaged by yarn on a bobbin whereby the slide may be moved inwardly of the support thereby, a transverse member on the inner end of the slide engageable with a part of the support to limit outward movements of the slide relative to the support, said slide and transverse member provided with longitudinal bores, a pilot slidable in said bores having an outer pointed end for projecting beyond the end surface of the slide, means on the inner end of said pilot engageable with the transverse member to limit outward movements of the pilot relative to the slide, a contact insulated from and fixed to the slide having a part disposed at the rear of the pilot to be engaged thereby, means to urge the pilot outwardly of the slide, separate means to urge the slide

outwardly of the support, said means including a compression spring around said pilot disposed in a recess provided in said slide with opposite ends between an end of the recess and a part provided on said pilot, and said separate means including a tension spring having opposite ends secured to a part provided on said support and a part provided on said slide that operates in a slot provided on the support.

2. A feeler device comprising in combination, 10 a support having a guideway, a slide reciprocable in said guideway having an open sided recess intermediate its ends and bores leading therefrom through opposite ends, means urging said slide outwardly of the support, a transverse member 15 on the inner end of the slide engageable with the support to limit outward movements of the slide relative to the support, a pilot reciprocable in the

bores of the slide and in the transverse member, means on the inner end of the pilot engageable with the transverse member to limit outward movements of the pilot relative to the slide, a contact fixed to and carried by the transverse member at the rear of the pilot to be engaged thereby as it moves inwardly of the slide, a compression spring around said pilot in the recess of the slide having an end in abutment with the end of said recess and its other end in engagement with a part provided on said pilot to urge the pilot outwardly of the slide, and a member secured to said support overlying the slide and retaining the same in said guideway and overlying and closing the recess therein.
